UNITED STATES PATENT OFFICE.

CHARLES W. FREID, OF GOOD THUNDER, MINNESOTA.

NONREFILLABLE BOTTLE.

1,425,957.

Specification of Letters Patent. Patented Aug. 15, 1922.

Application filed December 7, 1920. Serial No. 428,965.

To all whom it may concern:

Be it known that I, CHARLES W. FREID, a citizen of the United States, residing at Good Thunder, in the county of Blue Earth and State of Minnesota, have invented certain new and useful Improvements in Nonrefillable Bottles, of which the following is a specification.

This invention relates to improvements in non-refillable bottles.

The primary object of the invention is the provision of a bottle, embodying means which, while allowing escape of the contents of the bottles, will effectively prevent refilling thereof.

A further object of the invention is the provision of a non-refillable bottle of practical design, and one which can be easily and economically manufactured and assembled.

A further object of the invention is the provision of a non-refillable bottle, which cannot be refilled by submerging the bottle at any angle.

A further object of the invention is the provision of the non-refillable bottle of the above described character, which includes a buoyant valve construction to prevent refilling.

Other objects and advantages will be apparent during the course of the following detailed description.

In the accompanying drawings forming a part of this specification, and in which like characters designate like parts throughout the same:

Figure 1 is a fragmentary cross sectional view of the bottle having the improved non-refilling construction embodied therein.

Figure 2 is a cross sectional view taken on the line 2—2 of Figure 1.

Figure 3 is an enlarged cross sectional view taken on the line 3—3 of Figure 1.

In the drawings, wherein for the purpose of illustration is shown a preferred embodiment of my invention, the letter A designates a bottle of any approved type, having the retaining sleeve B, and the reciprocably mounted valve C, mounted within the neck D of the bottle A.

The bottle A while of any approved type, is preferably of such formation, that the neck D is sufficiently long to have formed therein the annular seat 10, near the outlet 11 of the neck D, and which is relatively long, being provided at the lower end thereof with the seating shoulder 12, and provided at the up-

per end with the instruck shoulder 14. A second seat 15, is provided in the neck D of the bottle, immediately below the annular seat 10, and which communicates with the annular seat 10 through the passageway 16 as defined by the seated shoulder 12; the second seat being preferably conical in formation, the enlarged end 17 lying adjacent the shoulder 12, and gradually tapering to the inlet 18, into the interior 19 of the bottle A.

The retaining sleeve B is adapted for seating within the annular seat 10, and is preferably formed of some non-corrosive material, preferably metal, which is sufficiently pliable to be adjusted into its position within the annular seat 10. The lower end 20 of the retaining sleeve B is adapted for seating upon the shoulder 12, the wall of the retaining sleeve B at the end 20 being relatively thick in comparison to the thickness of the walls at the end 21 of the retaining sleeve B, opposite the end 20. The passageway 22 within the sleeve B, is gradually constricted toward the inlet of the bottle. Overlapping baffles 24 and 25 are provided adjacent the end 20 of the sleeve B, and which are so formed that a passageway 26 is provided intermediate the free ends 27 of the retaining sleeve B; thus insuring removal of the contents of the bottle always travelling over a tortuous path upon the release thereof from within the bottle A. The baffles 24 and 25 have in reality been constructed to prevent the insertion of any article for tampering with the valve C, the construction of which will be hereinafter more fully disclosed. The upper end 21 of the sleeve B is adapted for engaging the instruck shoulder 14 to firmly retain the sleeve B in a fixed position within the neck D of the bottle A.

The valve C is preferably of glass or some analogous material, being preferably pyramidal in formation, and adapted for seating upon the conical seat 15, within the neck D of the bottle A. The interior 30 of the valve C is hollowed, and hermetically sealed by the structure of the valve itself, thus providing a buoyant body, adapted to float, when an attempt is made to refill the bottle by submerging the same at an angle, in order to seat itself upon the conical seat to prevent refilling the bottle A. Projections 31, preferably four in number, are provided upon the horizontal top surface 32 of the valve C, in order to provide free passageways 33, intermediate the ends 34 of the projection 31.

In the assemblage of the device, the bottle A is first filled with the desired substance, the valve C is then dropped through the neck D into position on the conical seat 5 15, it being understood, of course, that the largest dimension of the valve C is smaller than the entrance 16, as defined by the seating chamber 12, thus insuring that there will be no obstruction to the entrance of the valve 10 C. The retaining sleeve B is then inserted through the outlet 11 of the bottle A and into position within the annular seat 10, the lower end 20 of the sleeve B resting upon the seating shoulder 12. In order now to 15 make the sleeve B rigid with respect to the neck D of the bottle, the upper end 21 of the sleeve B is distorted, or inturned, by manual means, or upon some rotating tool, in such manner that the end 21 will rest 20 beneath and abut the instruck shoulder 14, thus providing that there will be a continuous and non-obstructed exit from the bottle, preventing tampering with the sleeve B for its removal.

25 In operation, to empty the contents of the bottle, the cork (not shown) is moved from the outlet of the bottle, and upon turning of the bottle to dispose the neck D downwardly, the valve C will by gravity drop, so 30 that the tops of the projection 31 will abut the undersurface 20 of the sleeve B, thus insuring that the liquid or contents of the bottle will flow freely past the valve, through the passageways 33 intermediate 35 the projection ways 31, into the interior of the sleeve B, through the passageway 26 as defined by the baffles 24 and 25, and outwardly through the outlet 11 of the bottle A. Since the valve acts by gravitation, and is 40 reciprocable within its seat in the neck D, it follows that upon disposal of the bottle A so that the neck D will be uppermost, the valve C will drop into its seat 15, thus sealing the entrance to the interior 19 of the 45 bottle A, and preventing refilling of the bottle. Should an attempt be made to fill the bottle by submerging the same in a liquid, and disposing the longitudinal axis of the bottle at any angle, the valve C, due to its 50 buoyancy will float to a closed position.

It is to be understood that the form of my invention herewith shown and described is to be taken as a preferred example of the same, and that various changes in the shape, size and arrangement of parts may be resorted to without departing from the spirit of the invention or the scope of the subjoined claims.

I claim:

60 1. In a non-refillable bottle, the combination of a bottle having a tapering seat therein adjacent the bottle opening, said seat converging inwardly of the bottle, a buoyant valve having downwardly converging 65 sides adapted for placement on the seat in

said bottle, and means for rendering said valve inaccessible, yet permitting operation thereof to empty the bottle, and prevent refilling thereof.

2. In a non-refillable bottle, the combination with a bottle, of a non-corrosive retaining sleeve of pliable material, and a valve disposed adjacent the retaining sleeve adapted for co-action therewith to permit emptying of the contents of the bottle and prevent the refilling of the bottle. 75

3. In a non-refillable bottle, the combination with a bottle, a neck upon said bottle having a seat near the outlet thereof, and a second seat immediately below said first mentioned seat, a retaining sleeve disposed upon said first mentioned seat, having an end thereof adapted to be distorted to engage said neck, to prevent removal therefrom, and a valve reciprocably disposed upon said second seat and adapted to co-act with said retaining sleeve to permit emptying of the contents of the bottle and preventing the refilling of the bottle. 80 85

4. In a non-refillable bottle, the combination, of a bottle having a neck thereon provided with an instruck annular seat near the outlet thereof, and a conical seat immediately below the first mentioned seat, a retaining sleeve adapted for disposal within 95 said first mentioned annular seat, the end thereof adapted to be inturned to tightly wedge the retaining sleeve within said seat, a hollow pyramidal shaped valve disposed reciprocably upon said conical seat immediately below said retaining valve, said valve and sleeve adapted to co-act to permit emptying of the contents of the bottle, and preventing the refilling of the same. 100

5. In a non-refillable bottle, the combination, of a bottle, having a neck thereon provided with an instruck annular seat near the outlet thereof, and a conical seat immediately below said annular seat, a retaining sleeve adapted to be disposed within said first mentioned annular seat and having an end thereof adapted to be inturned to tightly wedge the retaining sleeve within said seat, said retaining sleeve having overlapping baffle plates disposed upon the interior thereof, a hollow pyramidal shaped valve reciprocably mounted upon said conical seat immediately below said retaining sleeve and provided with projections thereon adapted for co-action against said retaining sleeve to provide a passageway for permitting emptying of the contents of the bottle, said valve acting under gravitation to assume its seat to prevent refilling of the bottle. 115 120 125

6. In a non-refillable bottle, the combination of a bottle having a seat therein adjacent the bottle opening, a float valve disposed on said seat, and a sleeve locked entirely within the bottle for rendering said 130

valve inaccessible, yet permitting operation thereof to empty the bottle and prevent refilling thereof.

7. The combination with a bottle having 5 a downwardly tapering seat in the neck thereof, a hollow downwardly tapering float valve disposed on said tapering seat, said valve having spaced lugs upwardly thereof, and a retaining sleeve in the neck of said 10 bottle upwardly of said valve seat, and normally spaced from said valve lugs when the valve is resting in its seat, said valve adapted for operation upon its seat to per-

mit emptying of the bottle and prevent refilling thereof. 15

8. In a non-refillable bottle, the combination of a bottle having a seat therein, a valve disposed upon said seat, and a non-corrosive retaining sleeve of pliable material adapted for distortion to retain the 20 same in the neck of said bottle upwardly of said valve, and for rendering said valve inaccessible to permit emptying of the contents of said bottle, and prevent refilling of said bottle.

CHARLES W. FREID.
